UNITED STATES PATENT OFFICE.

WEBSTER C. ESTES, OF NEW YORK, N. Y.

DESIGN FOR A WOODEN BOX.

40,467.

Specification for Design.

Patented Jan. 25, 1910.

Application filed November 10, 1909. Serial No. 527,353. Term of patent 14 years.

To all whom it may concern:

Be it known that I, WEBSTER C. ESTES, a citizen of the United States, residing in the borough of Manhattan, city, county, and State of New York, have invented a new, original, and ornamental Design for a Wooden Box, of which the following is a specification, reference being had to the accompanying drawing, forming part thereof.

In the drawing the figure is a perspective

view of a wooden box showing my new design.

I claim:

The ornamental design for a wooden box, as shown.

WEBSTER C. ESTES.
